DISPLAY STAND FOR EYEGLASSES OR THE LIKE

Jay L. Blomquist, 306 Busse Highway,
Park Ridge, Ill. 60667

Filed July 16, 1973, Ser. No. 379,793

Term of patent 14 years

Int. Cl. D20—02

U.S. Cl. D6—24

FIG. 1 is a perspective view showing a display stand for eyeglasses or the like in its general aspect, two pair of eyeglasses being shown retained thereon in phantom lines for illustrative purposes only;

FIG. 2 is a top plan view of the display;

FIG. 3 is a side or front elevational view of the display; and

FIG. 4 is a front or side elevational view of the display.

I claim:

The ornamental design for a display stand for eyeglasses or the like, as shown and described.
